UNITED STATES PATENT OFFICE.

FRANK KEARNS RADER, OF DALLAS, TEXAS.

MACHINE FOR USE IN TRIMMING SHRUBBERY.

Application filed January 23, 1928. Serial No. 248,930.

This invention relates to implements for use in connection with the care of shrubbery, and gardening, and it has particular reference to an improved, electrically operated 5 hedge trimming apparatus, the principal object of which resides in the provision of apparatus as designated by which to reduce to the very minimum the labor in pruning hedges and the like, yet increasing substantially 10 the efficiency and rendering this character of work less difficult to accomplish.

The invention further aims to provide an economical, yet durable machine for the purposes specified, requiring little attention and 15 provided with means by which it may be adjusted according to the density, or coarseness of the shrubbery upon which it is operated.

With the foregoing objects as paramount, the invention has further objects, as well as 20 certain salient features of construction and operation of parts, to become manifest as the description proceeds taken in connection with the accompanying drawings wherein:—

Figure 1 represents a perspective view of 25 an improved hedge trimming apparatus constructed according to the present invention, and

Figure 2 is a side elevational view of the 30 invention.

Continuing now more in detail with the drawings, 1 designates a motor of fractional horse power, preferably of the type employed in operating ventilating fans, since it is important that the apparatus as a whole be very 35 light in weight in order that it may be expeditiously manipulated in operation. To one side of the motor, which is the front of the device, is affixed a handle 2, and conveniently applied at the opposite side is another handle 40 3. These handles are arranged in such a manner as to enable the operator to hold the machine in operative position with minimum effort.

Affixed to the underside of the motor is a 45 metal plate 4, held by screws 5, which plate is so formed as to return beneath the portion 4 and form a guard 6, having a plurality of forwardly directed fingers and to engage the shrubbery as the machine is urged forward.

The motor drive shaft 8 is directed downwardly as shown in Figure 2 and has affixed thereto by set screw 9, a fly wheel 10, proportionately weighted as to maintain uniform motion of the circular saw 11, as imparted thereto by the motor 1, when the same cuts

into stubborn or tough shrubbery. The guard 6 is capable of being adjusted toward and away from the saw 11 by threaded studs 12, provided with exterior nuts 13, and lock nuts 14, in the event it becomes necessary in trimming shrubbery of varying density. Electrical current is supplied to the motor by way of wires 15, through fuse 16.

It is especially pointed out that the invention is particularly useful in pruning hedges of considerable length, the invention obviously saving time and labor due to its automatic operation and the ease by which it may be manipulated. Moreover, such use of the invention obviously enables the operator to obtain a more symmetrical appearance of the hedge or shrubbery over which the same is operated, and with greater speed, especially due to the cutting radius of the saw 11 and span of the guard 6.

In operation, the operator grips the handle 3 in one hand and the handle 2 in the other, and having previously arrived at the desired design to be carried out, the machine is run over the surface, severing the ends of the protruding shrubbery, until the hedge is properly shaped.

Obviously, the invention described is capable of some changes and modifications and such changes and modifications construed to be in keeping with the spirit of the invention may be made without departing from the scope of the appended claims therefor.

I claim:

1. A shrubbery trimming device including a substantially U-shaped resilient metal plate, a motor secured to the outer face of one side of the plate and having its shaft extending through said side, the other side of the plate having its free end formed with guard fingers which extend beyond the free end of the first named side, a cutter disposed adjacent to the inner face of the second named side and mounted on the motor shaft, a fly wheel also mounted on the motor shaft between the sides of the plate and engaged with the inner side face of the cutter, and threaded studs extending through each of the sides of the plate and having adjusting nuts thereon to increase or decrease the distance between the plate sides and thereby the relation of the second named side of the plate to the cutter.

2. A shrubbery trimming device including a substantially U-shaped resilient metal plate, a motor secured to the outer face of one side

of the plate and having its shaft extending through said side, the other side of the plate having its free end formed with guard fingers which extend beyond the free end of 5 the first named side, a cutter disposed adjacent to the inner face of the second named side and mounted on the motor shaft, a fly wheel also mounted on the motor shaft between the sides of the plate, and means connected to each of the sides of the plate to increase or decrease the distance between the 10 plate sides and thereby the relation of the second named side of the plate to the cutter.

3. A shrubbery trimming device includ- 15 ing a substantially U-shaped resilient metal

plate, a motor secured to the outer face of one side of the plate and having its shaft extending through said side, the other side of the plate having its free end formed with guard fingers which extend beyond the free 20 end of the first named side, a cutter disposed adjacent to the inner face of the second named side and mounted on the motor shaft, and means connected to each of the sides of the plate to increase or decrease the distance between the 25 plate sides and thereby the relation of the second named side of the plate to the cutter.

In testimony whereof I affix my signature.

FRANK KEARNS RADER.
